By W. S. Oliver Atty.

UNITED STATES PATENT OFFICE

2,118,777

ILLUMINATED SIGN

Hyman C. Hammer, Chicago, Ill., assignor to
 Price Brothers, Inc., Chicago, Ill., a corporation
 of Illinois

Application October 2, 1937, Serial No. 166,992

6 Claims. (Cl. 40—130)

This invention relates to signs generally, and more particularly to an illuminated sign, and has for its main object the provision of a sign structure, including a hollow casing within which a single source of illumination is utilized for producing in the same sign structure, the necessary illumination for lighting the edge of a glass panel to give an edge glow effect, said glass panel being arranged to close the forward open end of a hollow casing, the interior of which casing receives illumination from said single light source, said glass panel being opaque, except for a transparent peripheral border, with the result that when the interior of the hollow casing is illuminated, said transparent border will present the effect of a luminescent tube of illuminated neon gas or the like.

Another object of the invention is to provide a sign structure of the character described, including a casing open at its bottom and rear ends only, means for mounting a source of light within said casing, a glass panel arranged within a slot provided in the top wall of said casing, with the bottom edge of said panel disposed within said casing for receiving illumination therefrom, and a hollow member secured to the rear of said casing with the rear wall of said hollow member being spaced from the rear edge of said casing to provide communication between said casing and said hollow member for the passage of illumination into said hollow member, the forward portion of said hollow member being closed by said glass panel, said panel having its peripheral border only transparent, so that when said hollow member is illuminated, said transparent border will present the appearance of a luminescent tube, and the front wall of said casing being provided with an opening arranged for receiving a member bearing suitable indicia and to be illuminated by the light source within said casing.

A further object of the invention is to provide a sign structure of the character described which will be simple in manufacture, assembly and operation, which may be constructed along lines convenient for low-cost manufacture, and which will, at the same time, be highly efficient for carrying out the purposes for which it is designed.

With the foregoing and other objects in view, which will appear as the description proceeds, the invention consists in certain novel features of construction, arrangement and combination of parts hereinafter more fully described, illustrated in the accompanying drawing, and particularly pointed out in the appended claims, it being un-

derstood that various changes in the form, proportion, size and minor details of the structure may be made without departing from the spirit or sacrificing any of the advantages of the invention.

For the purpose of facilitating an understanding of my invention, I have illustrated in the accompanying drawing a preferred embodiment thereof, from an inspection of which, when considered in connection with the following description, my invention, its mode of construction, assembly and operation, and many of its advantages should be readily understood and appreciated.

Referring to the drawing, in which the same characters of reference are employed, to indicate corresponding or similar parts throughout the several figures of the drawing:

Fig. 1 is a front elevational view of a sign structure embodying the principles of my invention, parts thereof being broken away to illustrate the interior construction thereof;

Fig. 2 is a transverse sectional view through the same taken substantially on line 2—2 of Fig. 1;

Fig. 3 is an end elevational view of the same;

Fig. 4 is a bottom plan view of the same;

Fig. 5 is a sectional view taken substantially on line 5—5 of Fig. 1;

Fig. 6 is a view taken substantially on line 6—6 of Fig. 2.

The structure illustrated in the drawing and forming the basis of the present application, is an improvement on an application filed by myself August 9, 1937 and bearing Serial No. 158,089.

Referring to the drawing more specifically by characters of reference, the numeral 10 designates generally a hollow base which may be formed of any suitable material, such as cast metal or the like, and which may assume any size or shape. Said hollow base is provided with the side walls 11, the front wall 12 and the top wall 13, and being open at its bottom and rear.

The open bottom wall of said hollow base is adapted to be closed by a plate member 14 of sheet metal or the like, which member is detachably secured in place to said hollow base by means of the screws 15, which extend through the plate member 14 and are received in threaded relation in screw-threaded openings provided therefor in the end walls 11 of said hollow base member 10.

Carried on the inner face of the plate member 14 are the lamp sockets 16, there being one of said sockets arranged adjacent each end of said

plate member 14, and each of said sockets is provided with a light bulb 17. A conducting cord 18 is connected to the lamp sockets, which cord leads to a source of electric current. The light bulbs 17 disposed within said hollow base 10 are adapted for producing the desired illumination for the entire sign structure. In order to permit the circulation of air through said hollow base member and to keep the same cool, I provide a 10 plurality of openings 19 within the plate member 14, which openings are shielded to prevent the passage of light therethrough by a plate member 20 secured to the inner face of the plate member 14, the outer edges 21 of which are turned upwardly, as shown in Fig. 2, to permit the passage 15 of air into the casing, but to prevent the passage of light through said openings 19.

The front wall of said hollow base 10 is provided intermediate the ends thereof with an 20 opening 23, which opening is adapted to be closed by a suitable member 24 of glass or other suitable material, upon which member may be provided desired transparent indicia such as reading matter and the like for advertising purposes, said 25 member 24 being illuminated directly by the light source 17 when the sign is in operative condition. The member 24 may be held in place against the opening 23 by means of the clips 25, detachably secured in place to the inner face of 30 the front wall of the hollow base 10 by means of the screws 26.

Provided in the upper wall 13 of said hollow base is a slot 27 which extends substantially across the full length of said hollow base, and 35 within which slot is adapted to be disposed a glass panel 28 with the bottom edge thereof being received within the hollow base as shown more clearly in Figs. 2 and 5, so that said edge may be illuminated by the light source 17 disposed 40 within said hollow base.

Attached to the rear of said member 28 is an opaque member 29, upon which may be provided suitable reading matter for advertising purposes and the like, said member 29 covering substantially the entire rear surface of said member 28, except for a narrow band 30 extending around the peripheral border of said member 28, which band is left transparent for a purpose to be 45 presently more fully described.

50 The structure so far described is provided with a back 31, shaped substantially as shown in the drawing, and formed of suitable sheet metal or the like, said back being secured to the side walls of the hollow base 10 by means of the 55 screws 32 or in some other suitable and well known manner, and when in assembled position will form with said hollow base and panel 28 a substantially closed compartment 33, which will communicate by means of the passage 34 with the interior of the hollow base carrying the light 60 source 17.

As illustrated in Fig. 1 of the drawing, the panel 28 is arranged so as to substantially close the entire forward opening of the member 31. 65 The said member 31 has its interior surface provided with a coating of suitable paint or the like to give to the same a relatively dull finish and also a smooth and uniform surface. The result of this arrangement is that the entire 70 interior of the compartment 33 will be illuminated when the light source 17 is illuminated and as the panel 28 has a backing 29 of opaque material provided thereon, said backing will be effective for blocking out all of the illuminated 75 interior of the compartment except for the nar-

row band around the edge of the interior which may be viewed through the transparent band 30 on the panel 28. As the embodiment illustrated is to be used as a counter sign, the plate member 14 has secured thereto adjacent each end thereof, 5 the cross members 35, to the free ends of which may be attached the rubber feet 36, so as to avoid injury to the surface upon which the sign may be disposed.

From the above it will be apparent that when 10 the light bulbs 17 are connected to a source of current, it will illuminate the interior of the hollow base as well as the interior of the back member 31, with the result that the panel 24 will be illuminated, producing a so-called bull's-eye 15 effect. The edge of the panel 28 will likewise be illuminated, producing the so-called well-known edge-glow effect, while, at the same time, the transparent band 30 of said panel 28 will permit a view of the edge portion of the hollow 20 illuminated interior of the compartment 33 which in effect will produce a band of light substantially of a width equal to that of the transparent band 30 of the panel 28, thus presenting the effect of a luminescent tube of light, thereby giving 25 the sign a highly attractive and unique appearance. It will also be noted that this highly desired result is accomplished with a very simple structure containing only a minimum number of parts and only a single source of illumination. 30 It is to be understood that I do not limit myself to the specific shape or size of the sign structure illustrated, as the desired effects may be produced by a sign of any size or shape having a compartment for receiving a source of 35 illumination, which compartment is in communication with a second compartment so as to permit the passage of light from said first compartment into said second compartment, the forward wall of said second compartment being closed 40 by a member, the edge of which receives illumination from the first compartment and the outer periphery of which is provided with a transparent band so that when said second compartment is illuminated, it will produce the effect 45 of a luminescent tube.

It is believed that my invention, its mode of construction and assembly, and many of its advantages should be readily understood from the foregoing without further description, and 50 it should also be manifest that while a preferred embodiment of the invention has been shown and described for illustrative purposes, the structural details are nevertheless capable of wide variation within the purview of my invention as 55 defined in the appended claims.

What I claim and desire to secure by Letters Patent of the United States is:

1. A sign of the character described, comprising a casing having a top, front and side walls, a 60 detachably secured bottom wall for said casing and a source of illumination mounted on the inside of the said bottom wall, a slot formed in the top wall of said casing, a glass panel having its bottom edge disposed within said slot, 65 and a back secured to said casing and arranged to form therewith a closed lower compartment, said back extending upwardly from said casing and arranged to form with said glass panel an upper compartment, said two compartments being 70 in communication with each other to permit the passage of light from the lower compartment to the upper compartment, the forward open portion of said upper compartment being closed by the glass panel and an opaque member 75

arranged on the rear face of said glass panel and covering substantially the entire surface thereof except for a peripheral border, and a source of illumination mounted within said lower compartment whereby when said lower compartment is illuminated, it will be effective for illuminating the bottom edge of said glass panel as well as the interior of the upper compartment, with the result that the transparent peripheral border of said panel will present the effect of a luminescent tube.

2. A sign of the character described, including a lower and upper compartment, said lower compartment having a source of illumination mounted therein, which when illuminated will also provide illumination for the upper compartment, said upper compartment extending upwardly and rearwardly of said lower compartment, a glass panel for closing the forward portion of said upper compartment and having its bottom edge disposed within the lower compartment for receiving illumination therefrom, said glass panel being opaque throughout its entire surface except for a peripheral transparent border, whereby when the sign is illuminated said transparent border will present the effect of a luminescent tube.

3. A sign of the character described, including a lower compartment and an upper compartment extending rearwardly and upwardly of said lower compartment, a glass panel for closing the forward portion of said upper compartment and having its bottom edge disposed within said lower compartment for receiving illumination therefrom, a source of light mounted within said lower compartment and being adapted for illuminating said glass panel as well as the interior of said upper compartment, an opaque member mounted on the rear surface of said glass panel and covering substantially the entire rear surface thereof except for a peripheral border, whereby upon the illumination of the interior of said upper compartment said transparent border will present the effect of a luminescent tube.

4. A sign of the character described, including a casing having a top, front and side walls, said front wall being provided with a translucent indicia bearing member, a glass panel carried by the top wall of said casing and having its bottom edge disposed within said casing for receiving illumination therefrom, a detachably secured bottom wall for said casing, a light source mounted on the interior of said bottom wall for illuminating said casing and a back secured to said casing

arranged to form therewith a closed lower compartment, said back extending upwardly and rearwardly of said casing, said upper portion thereof forming with said glass panel an upper compartment which is in communication with said lower compartment for receiving illumination therefrom, said glass panel having an opaque member arranged on the rear surface thereof, the peripheral edge of said opaque member being spaced from the peripheral edge of said back member, whereby when the upper compartment is illuminated the light passing through said space will present the effect of a luminescent tube.

5. A sign of the character described, including a casing formed so as to provide a lower compartment and an upper compartment extending inwardly of said front face of said lower compartment, a source of illumination mounted in said lower compartment and adapted for illuminating both of said compartments, the forward portion of said upper compartment being closed by a glass panel, the bottom edge of which is disposed within said lower compartment for receiving illumination therefrom, an opaque member mounted on the rear surface of said glass panel and covering substantially the entire panel except for a peripheral border, whereby said border will permit the passage of light therethrough when the sign is illuminated to present the effect of a luminescent tube.

6. A sign of the character described, including a casing formed so as to provide a lower compartment and an upper compartment extending inwardly of said front face of said lower compartment, a source of illumination mounted in said lower compartment and adapted for illuminating both of said compartments, the forward portion of said upper compartment being closed by a glass panel, the bottom edge of which is disposed within said lower compartment for receiving illumination therefrom, an opaque member mounted on the rear surface of said glass panel and covering substantially the entire panel except for a peripheral border, whereby said border will permit the passage of light therethrough when the sign is illuminated to present the effect of a luminescent tube, the front wall of said lower compartment being provided with an opening intermediate the ends thereof adapted for receiving a translucent indicia bearing member which will be illuminated by the source of illumination mounted within said compartment.

HYMAN C. HAMMER.
